United States Patent Office

Des. 173,656
Patented Dec. 14, 1954

173,656

TIRE DISPLAY STAND

Ralph M. Heckman, Denver, Colo., assignor to The Gates
Rubber Company, Denver, Colo., a corporation of
Colorado

Application April 5, 1954, Serial No. 29,856

Term of patent 14 years

(Cl. D80—10)

Fig. 1

Fig. 2

Fig. 3

To all whom it may concern:

Be it known that I, Ralph M. Heckman, a citizen of the United States, residing at Denver, county of Denver, State of Colorado, have invented a new, original, and ornamental Design for a Tire Display Stand, of which the following is a specification, reference being had to the accompanying drawings, forming part thereof, and in which:

Fig. 1 is a perspective view of a tire display stand, embodying the design of this invention;

Fig. 2 is a partial front elevation of the tire display stand of Fig. 1; and

Fig. 3 is a side elevation of the tire display stand of Fig. 1.

I claim:

The ornamental design for a tire display stand, as shown.
